CONTINUOUS AUTOMATIC FLUID-PRESSURE BRAKE FOR RAILWAY AND LIKE VEHICLES.

1,387,035.

Specification of Letters Patent.

Patented Aug. 9, 1921.

Application filed June 28, 1919. Serial No. 307,290.

To all whom it may concern:

Be it known that I, ARTHUR MORTON BELL, a subject of the King of Great Britain, and resident of 7 Khatau Mansions, Bombay, India, have invented a certain new and useful Improvement in Continuous Automatic Fluid-Pressure Brakes for Railway and like Vehicles, of which the following is a specification.

10 This invention relates to continuous automatic fluid-pressure brake apparatus for railway and like trains (more particularly goods trains) wherein, for the purpose of enabling the potential brake-power of a vehicle to be definitely adjusted to meet the requirements arising from either the loaded or the empty condition as the case may be, such vehicle is provided with a supplementary brake-cylinder whereof the piston is 15 adapted to actuate the brake-shaft of the vehicle concurrently with the piston of the primary or normally-operative brake-cylinder, and a device (hereinafter termed a control-valve) whereby to effect on the one hand 20 the manual throwing into potential operation, and on the other hand the automatic cutting-out of said supplementary brake-cylinder according as it is required to exchange the braking capabilities of the vehicle 25 from those proper to an empty to those proper to a loaded vehicle, or vice versa.

The primary object of the present invention is to provide an improved construction of control-valve for use in combination with 30 the supplementary brake-cylinder and with a supplementary fluid-pressure reservoir and other necessary devices and connections for enabling the requisite supply of fluid under pressure (hereinafter referred to as compressed air) to be furnished to the supplementary brake-cylinder.

The improved control-valve is interposed in a connection between the train-pipe and the triple-valve of the supplementary air-reservoir and brake-cylinder of the vehicle, and comprises the control-valve itself (properly so-called) which, on the one hand, constantly tends under spring-action to assume the closed position wherein it cuts off communication between the train-pipe and the supplementary air-reservoir and brake-cylinder, and which, on the other hand, is

adapted to be brought, by means of a manually-operable cam, to the open position wherein it establishes such communication 55 and thus renders the supplementary brake-cylinder potentially operative in conjunction with the primary (or normally-operative) brake-cylinder of the vehicle. Means are provided whereby, when pressure exists in 60 the supplementary air-reservoir (as during ordinary working conditions), although the control-valve still remains open, the cam becomes potentially freed to spring-action in 65 in such manner that, on the brakes being completely released or allowed to leak-off (as when the vehicle is put aside with a view to being unloaded), the cam will be automatically restored to inoperative position, thus permitting the automatic return of the control valve itself to its closed position. 70

In the accompanying drawings, which illustrate one form of the improved control-valve and parts immediately associated therewith, Figure 1 shows the valve in the 75 closed position, Fig. 2 shows the same in the open position, Fig. 3 shows the valve in the intermediate (but still open) position which it assumes during ordinary working conditions when the vehicle to which it is applied is being run loaded, and Fig. 4 is a 80 diagrammatic view illustrating the relation between the improved control-valve, the train pipe and the supplementary brake-cylinder with its air reservoir and triple-valve, as 85 well as the primary brake-cylinder with its air-reservoir and triple-valve. In each figure the valve-casing is represented in axial section.

Referring first to the diagram, Fig. 4, *a* is 90 the train-pipe, *b* the primary (or normally operative) brake-cylinder, *c* the primary air-reservoir, and *d* the primary triple-valve which as usual controls the connection between the train-pipe *a* and the air-reservoir 95 *c* and between said reservoir and the brake-cylinder *b*. The construction of these parts and their interconnections and mode of operation are well known in the art and need not be further described. *b'* is the supplementary brake-cylinder, *c'* the supplementary air-reservoir, and *d'* the supplementary triple-valve, all of which are of usual construction and adapted to operate in the well 100

known manner; while the improved control-valve is shown at *e*. The connections between the supplementary brake-cylinder *b'* and its triple-valve *d'*, and between the latter and the supplementary air-reservoir *c'*, are as usual, but the control-valve *e* serves to control the connection between the train-pipe *a* and the supplementary triple-valve *d'* as hereinafter explained.

10 In the example illustrated, the control-valve comprises a piston-valve *11* of substantially D-form fitted to slide to-and-fro in a cylindrical casing *12* so as to alternatively open or close communication between 15 two ports *13*, *14* in the wall of the casing, these ports being permanently connected, the one *13* by a pipe *15* with the train-pipe *a* and the other *14* by a pipe *16* with the triple-valve *d'* of the supplementary air-reservoir *c'* and brake-cylinder *b'*. Between 20 the left-hand end of the valve-piston *11* and the adjacent end-closure *17* of the casing *12*, is interposed under compression, a spring *18* (hereinafter termed the valve-spring) 25 constantly tending to cause the piston *11* to move toward the right so as to assume the closed position shown in Figs. 1 and 4 wherein communication between the two ports *13*, *14* is cut off; while the space *19* between 30 the right-hand end of the valve-piston *11* and the corresponding end-closure *20* of the casing constitutes what may be termed a variable air-pressure chamber in the wall of which is a third port *21* in permanent 35 communication by a pipe *22* with the supplementary air-reservoir; the force exerted upon the piston *11* in the one direction by the valve-spring *18* being less than that exerted upon it in the opposite direction by the 40 air-pressure in the space *19* when normal working pressure exists within the supplementary reservoir *c'*.

The piston rod *23* of the valve-piston *11* extends outward toward the right through 45 a stuffing-box *24* at the end of the space *19*, and has attached to it, externally at *25*, a rod *26* which is movable to-and-fro as one with the piston *11* in a guide *27*, and through a slot *28* in this rod extends a cam-bar *29* 50 which is slidable in guides (whereof one *30* alone is shown) transversely of the rod *26*. The cam-bar *29* constantly tends to assume the inoperative position illustrated in Figs. 1 and 4 under the pressure of a spring *31* 55 (hereinafter termed the cam-spring) in opposition to which it can be moved by hand to the fully set position shown in Fig. 2; the spring *31* being shown as confined between the guide *30* and a collar *32* on the cam-bar, 60 while in Fig. 4 the cam-bar is shown as provided with a handle *h*. The left-hand edge of the car-bar *29* presents, for engagement with the adjacent end *33* of the slot *28*, an inclined cam-face *34* which, when the bar 65 is moved by hand against the spring *31*

to the fully set position (ordinary atmospheric pressure being assumed to exist at this time in the chamber *19*), causes displacement of the valve from the closed position shown in Figs. 1 and 4 to the open position 70 shown substantially in Fig. 2, the cam-bar *29*, on reaching the fully set position, becoming locked therein by the engagement of the end *33* of the slot *28* over a shoulder *35* at the termination of the cam-face *34*. 75 It will be observed that this locking is due to the action of the valve-spring *18* which, after the cam-face *34* has passed completely through the slot *28*, returns the valve *11* a short distance toward the right until arrested by the cam-bar *29*, beyond the shoulder *35*, whereas the admission of air at working pressure to the chamber *19* will, by moving the valve *11* toward the left, disengage the shoulder *35* and release the cam-bar *29* to 80 action of its spring *31*. It is obvious, however that if, on such release, the cam-bar were permitted to return immediately to its initial or idle position (Figs. 1 and 4), there would be a possibility of the valve *11* closing, prematurely, the connection between the ports *13* and *14* as a result of *e.g.* shock or excessive vibration during the running of the train. Means are therefore provided for insuring that the ultimate restoration of 85 the cam-bar *29* to its initial or idle position (Figs. 1 and 4) shall be effected not as the result of such movement of the valve *11* toward the left, but as the result of a subsequent movement of the valve *11* toward the 90 right due to the pressure in the chamber *19* falling below that of the valve-spring *18* when the pressure within the supplementary air-reservoir *c'* drops as hereinafter stated. 95

For this purpose the cam-bar *29* is provided at its right-hand edge with a shoulder *36* so situated relatively to the shoulder *35* at the left-hand edge that the release of the shoulder *35* (in consequence of the rise of pressure in the chamber *19* and movement 100 of the valve *11* toward the left) will be immediately followed by the re-arrest of the cam-bar *29* owing to the engagement of the shoulder *36* against the right-hand end *37* of the slot *28* as shown in Fig. 30. The 105 cam-bar *29* now occupies what may be termed the "half set" position (Fig. 3), wherein the valve *11*, being in what has been referred to as its intermediate position, still remains open; the final release 110 of the cam-bar and its return to the idle position (Figs. 1 and 4) following upon the disengagement of the shoulder *36* in consequence of the fall of pressure in the chamber 115 *19* and movement of the valve *11* toward the right, which fall of pressure occurs only when the vehicle has been put away for unloading and the brakes on the vehicle have leaked off. The cam-bar *29* is of such width 120 between the shoulders *35* and *36* (one of 125 130

which is slightly in advance of the other) as to be only just capable of passing through the slot 28, so that the end 37 of the slot cannot fail to come into position to engage 5 the shoulder 36 as soon as the end 33 of the slot becomes disengaged from the shoulder 35, and hence a premature return of the cam-bar 29 to its initial or idle position (Figs. 1 and 4) cannot occur.

10 In operation, when a loaded vehicle has been coupled-up to the brake-system of a train, the cam-bar 29 is moved by hand against the pressure of the cam-spring 31 so as to bring the control-valve piston 11, by 15 the action of the cam-face 34 against the end 33 of the slot 28, from the closed position shown in Fig. 1 to the open position shown in Fig. 2, in opposition to the valve-spring 18, the cam-bar 29 becoming locked in 20 the operative position by engagement of its shoulder 35 with the slotted rod. After the train-coupling operation is complete and the brake apparatus charged with air, the air-pressure maintained in the train-pipe *a* during 25 the continuance of ordinary running conditions gains access, by way of the pipe 15, port 13, valve-piston 11, port 14, and pipe 16, to the supplementary air-reservoir *c'* and thence to the variable air-pressure 30 chamber 19, and, by exerting a pressure against the valve-piston 11 further moving the latter in opposition to the valve-spring 18, causes the shoulder 35 on the cam-bar 29 to become freed from the slotted rod 26 so 35 as to permit the engagement with the latter of the shoulder 36, as shown in Fig. 3. So long as normal working air-pressure is maintained in the supplementary air-reservoir *c'* and variable air-pressure chamber 40 19, the supplementary brake-cylinder *b'* remains capable of operating in conjunction with the primary brake-cylinder *b* of the vehicle, as is required for braking the vehicle when loaded, this state of affairs continuing 45 so long as the vehicle remains coupled-up with the train and the latter is kept under running conditions.

When the vehicle is put aside for unloading, the complete release of pressure 50 from the brake apparatus (consequent upon the opening of the train-pipe *a* and the leaking-off of the brakes) reduces the pressure within the supplementary air-reservoir *c'* and variable air-pressure chamber 19 55 until the valve-spring 18 is enabled to return the control-valve piston 11 to the closed position, Fig. 1; the shoulder 36 on the cam-bar 29 being by this action freed from the slotted rod 26 so that the cam-spring 31 is enabled to return the cam-bar 60 completely to the inoperative position shown in Fig. 1. The supplementary air-reservoir *c'* and variable air-pressure chamber 19 being now cut off from the train-pipe *a* by 65 the closure of the control-valve, it follows

that, if the unloaded vehicle be again put into running condition, the supplementary brake-cylinder *b'* will remain inoperative, as is required for braking the vehicle when empty.

70

I claim:

1. In an automatic fluid-pressure brake apparatus, the combination of a train-pipe, a supplementary fluid-pressure reservoir, a supplementary brake-cylinder, a triple valve connected with said reservoir and said cylinder, a connection between the triple valve and the train-pipe, a control-valve in said connection, a spring under the action of which said valve constantly tends to assume a closed position in which said connection is closed, a manually-operable cam for moving said valve to an open position in which said connection is open, a spring for restoring said cam to its inoperative position and means whereby, when pressure exists in the supplementary fluid-pressure reservoir, although the control-valve still remains open, said cam becomes potentially freed to the action of said spring in such a manner that, on the brakes being completely released or allowed to leak off, the cam will be automatically restored to inoperative position, thus permitting the automatic return of the control-valve itself to the closed position, substantially as and for the purpose set forth.

90

2. In an automatic fluid-pressure brake apparatus, the combination of a train-pipe, a primary braking mechanism connected therewith, a supplementary braking mechanism connected with said train-pipe and arranged to supplement the action of said primary braking-mechanism, controlling-means whereby the connection between said supplementary braking mechanism and said train-pipe is controlled, manually operable means for actuating said controlling-means to open said connection, said controlling-means being maintained in open position by pressure in said supplementary braking mechanism and means whereby said manually operable means is automatically restored to its inoperative position and said controlling-means is automatically actuated to close said connection when said pressure is released.

95

3. In an automatic fluid-pressure brake apparatus, the combination of a train-pipe, a primary braking mechanism connected therewith, a supplementary braking mechanism connected with said train-pipe and arranged to supplement the action of said primary braking-mechanism, controlling-means whereby the connection between said supplementary braking mechanism and said train-pipe is controlled, a cam whereby said controlling-means is actuated to open said connection, said cam being held by said controlling-means and being released as pressure in said supplementary braking mech-

anism drops and means for automatically causing said controlling-means to close said connection when said cam is released.

4. In an automatic fluid-pressure brake apparatus, the combination of a train-pipe, a primary fluid-pressure reservoir, a primary brake-cylinder, a primary triple-valve connected with said train-pipe, said brake-cylinder and said reservoir, a supplementary fluid-pressure reservoir, a supplementary brake-cylinder connected therewith, a supplementary triple-valve in said connection, a valve-casing, a connection from said valve-casing to said train-pipe, a connection from

said supplementary triple-valve to said 15 valve-casing, a controlling-valve in said casing whereby communication between said two last named connections is controlled, a spring at one end of said valve whereby the latter constantly tends to assume a position 20 in which said communication is closed, a connection leading from said valve-casing behind the other end of said valve to said supplementary fluid-pressure reservoir and a manually operable cam whereby said valve 25 is actuated against the tension of said spring to open said communication.

ARTHUR MORTON BELL.
